UNITED STATES PATENT OFFICE.

JAMES H. HALL, OF CHICAGO, ILLINOIS.

LACING-HOOK.

1,269,076.

Specification of Letters Patent. Patented June 11, 1918.

Application filed June 30, 1916. Serial No. 106,804.

To all whom it may concern:

Be it known that I, JAMES H. HALL, a citizen of the United States, residing at Chicago, in the county of Cook and State 5 of Illinois, have invented certain new and useful Improvements in Lacing-Hooks, of which the following is a description.

My invention belongs to that general class of devices known as lacing hooks, and particularly hooks for use on shoes for engagement with the shoe laces. The use of the same, however, is not limited to shoes, as the same may be used upon gloves or other apparel, or articles upon which the same 10 may be applicable. The invention has among its objects the production of a device of the kind described that is simple, convenient, efficient and satisfactory, and which may be inexpensively manufactured 15 and applied. It has particularly among its objects the production of a fastener in which the hook is substantially guarded or protected so that the same will not easily and accidentally engage with the wearing 20 apparel of the user, and particularly with skirts and the like, when the fastener is employed on ladies' shoes. It also has as a further object the production of a fastener or hook of the kind described that 25 may be securely and firmly attached to the shoe in such a manner that it will not easily pull out. Many other objects and advantages of the construction herein shown and described will be obvious to those skilled in 30 the art from the disclosure herein made.

To this end my invention consists in the novel construction, arrangement and combination of parts herein shown and described and more particularly pointed out in the 35 claims.

In the drawings, wherein like reference characters indicate like or corresponding parts,

Figure 1 is a front elevation of several devices applied to wearing apparel;

Fig. 2 is a side elevation of one of the devices;

Fig. 3 is a sectional view through the same;

Fig. 4 is a perspective view, and

Fig. 5 is a sectional view, similar to Fig. 3, of a simplified construction.

Referring to the drawings, in which the preferred forms of the devices are shown, 55 1 and 2 represent two desired parts to be laced and secured together by means of a

suitable lacing 3 of any desired material or construction. The fastener consists of a tubular head 4, which is preferably cut away at each side, substantially as indicated at 60 5—5, so as to receive the lacing 3 when the device is in use. The head is preferably formed with a projecting part or hook 6, extending over the same, the outer or free end 7 of which may be slightly depressed, 65 as most clearly shown in Fig. 3. The purpose of depressing the same is to bring the end slightly below the top of the head. The side of the head opposite the hook at each side thereof forms substantially a guard 8, 70 the top of which is preferably above the end 7 of the hook. In the construction shown in Figs. 1-4, I show a slight flange 9 extending inwardly about the upper edge or rim 8 of the head, the hook 6 in flange 9, however, being so proportioned that the space 10 between the hook and rim will permit the lace to be easily pushed into place and engage under the hook. The flange 9 is not necessary or essential and may be omitted if 75 desired, as shown in the section illustrated in Fig. 5, in which the edge of the guard 8 is preferably slightly rounded as at 9', the space 10' in this case being somewhat larger than the space 10 shown in Fig. 3. 85

As shown, the head is provided with a tubular shank 11, which is of sufficient length so that the outer end 12 of the same may be turned over or flanged outwardly to engage the material 1, and secure the 90 fastener in place. As most clearly shown in Figs. 3 and 4, the base of the head forms a shoulder about the shank 11, and if desired, the same may be so arranged that the edge 15 will tend to impinge in the material 95 1, as shown. In applying the fastener the flange 12 is also formed to impinge as at 16, after the flange has been set, the flange being formed after the shank has been passed through the material, so that when 100 the fastener is in place the edge of the material about the opening through which the fastener or shank passes will be firmly gripped and locked, as most clearly shown in the two figures referred to. Where the 105 fasteners are used on shoes a lining 17 may be, and is ordinarily used to cover the inner end of the shank and prevent chafing.

Assuming the fasteners are applied as described, or in an equivalent manner, the 110 same being constructed as illustrated in Figs. 3 or 5, the lace is pushed into the

space 10 or 10', as the case may be, and as it is drawn tight, it drops into the spaces or notches 5 (see Fig. 1), where it is firmly and securely engaged. If the flange 9 is employed this will, to some extent, tend to prevent the accidental disengagement of the lace in case the same becomes loosened. As mentioned, however, the flange 9 is not essential. It will be noted by referring to the several figures, that there is nothing upon which the wearing apparel may accidentally engage and become torn, as for example, skirts and the like, where the fastener is used on ladies' shoes. The fastener not only prevents accident to the wearing apparel, but by preventing engagement with the same, may in many cases prevent serious accidents, such as falls or the like. The fastener is not confined in its use to ladies' shoes alone, that is, it may be used on men's shoes, on gloves, leggings, corsets, and, in fact, any place where a lace fastening may be found desirable.

Having thus described my invention, it is obvious that various immaterial modifications may be made in the same without departing from the spirit of my invention; hence I do not wish to be understood as limiting myself to the exact construction, arrangement and combination of parts herein shown and described, or uses mentioned.

What I claim as new and desire to secure by Letters Patent is:—

1. A lacing member of the kind described, comprising a tubular head, provided with a shank at one end and with a shoulder

about the shank at its juncture with the head, said head provided with a projecting hook at one side extending across the head to adjacent the other side thereof, and slightly depressed at its free end below the top edge of the head, said head inwardly flanged about said hook end and cut away at each side of the hook to adjacent the base, the outer edge at the shoulder on the under side of the base of the head formed to impinge into the material carrying the member, and the shank of sufficient length to permit the same to be flanged outwardly and inwardly and impinge at its free ends into the material carrying the member.

2. A lacing member of the kind described, comprising a tubular head, provided with a suitably formed shank at one end and with a hook at the opposite end, said hook extending across the head to proximate the other side, said head cut away at each side of the hook adjacent its juncture with the base to a point near the bottom of the base, said other side of the head extended to constitute a coöperating guard about the free end of the hook, and flanged inwardly about the end of the hook, with a space between the edge of the flange and sides and end of the hook.

In testimony whereof, I have hereunto signed my name in the presence of two subscribing witnesses.

JAMES H. HALL.
